(57) **CLAIM**

The ornamental design for a pressure cooker, as shown and described.

DESCRIPTION

FIG. 1 is a front, top and right-side perspective view of a pressure cooker showing our new design;

FIG. 2 is a front view thereof;

FIG. 3 is a rear view thereof;

FIG. 4 is a top view thereof;

FIG. 5 is a bottom view thereof;

FIG. 6 is a right-side view thereof;

FIG. 7 is a left-side view thereof; and,

FIG. 8 is a rear, top and left-side perspective view thereof. The broken lines shown depict portions of the pressure cooker that form no part of the claimed design.
